DESIGN FOR A CANDELABRUM

George R. Bunker, Omaha, Nebr.

Application September 23, 1948, Serial No. 148,736

Term of patent 3½ years

(Cl. D48—2)

To all whom it may concern:

Be it known that I, George R. Bunker, a citizen of the United States, residing at Omaha, in the county of Douglas and State of Nebraska, have invented a new, original, and ornamental Design for a Candelabrum, of which the following is a specification, reference being had to the accompanying drawing, forming part thereof.

Figure 1 is a perspective view of a candelabrum, showing my new design;

Figure 2 is a cross-sectional view, taken substantially in the plane of the line 2—2 in Figure 1.

I claim:

The ornamental design for a candelabrum, as shown.

GEORGE R. BANKER.
